DESIGN FOR A CONTAINER CAP

Philip A. Derham, Rosemont, Pa., assignor to
Victor Metal Products Corporation, Brooklyn,
N. Y., a corporation of New York

Application February 18, 1946, Serial No. 126,665

Term of patent 14 years

(Cl. D58—26)

To all whom it may concern:

Be it known that I, Philip A. Derham, a citizen of the United States, residing at Rosemont, in the county of Montgomery and State of Pennsylvania, have invented a new, original, and ornamental Design for a Container Cap, of which the following is a specification, reference being had to the accompanying drawing, forming part thereof.

Fig. 1 is a top plan view of a container cap, showing my new design.

Fig. 2 is an elevational view thereof.

Fig. 3 is a bottom plan view thereof.

I claim:

The ornamental design for a container cap, substantially as shown.

PHILIP A. DERHAM.
